PUMP

Werner E. Armstrong, Milwaukee, Wis., assignor
to Briggs & Stratton Corporation, Milwaukee,
Wis., a corporation of Delaware

Application May 2, 1945, Serial No. 591,453

5 Claims. (Cl. 103—150)

1

This invention relates to pumps and has particular reference to fuel pumps of the type used on internal combustion engines.

One of the objects of the present invention resides in the provision of an inexpensive improved fuel pump which is especially suited for use with small portable internal combustion engines.

More specifically it is an object of this invention to provide a fuel pump of the character described with a valve chamber formed as an integral part of the fluid passageway in the body of the pump and in which the check valves are readily detachably mounted.

Another object of this invention resides in the provision of a check valve of novel unitary design which is especially suited for diaphragm operated fuel pumps.

A further object of this invention resides in the provision of a novel lost motion connection between the operating lever and the diaphragm of a fuel pump of the character described.

With the above and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed in accordance with the best mode so far devised for the practical application of the principles thereof, and in which:

Figure 1 is a cross sectional view through the fuel pump of this invention;

Figure 2 is a sectional view through the valve chamber of the pump taken on the plane of the line 2—2 of Figure 1;

Figure 3 is a perspective view of a portion of the pump body showing the entrance to the valve chamber and illustrating the various elements constituting the valve assembly of the pump with the parts shown in the order of their assembly; and

Figure 4 is a perspective view of one of the check valves of this invention with the parts thereof disassembled but in their proper positional relationship with respect to the valve body.

Referring now more particularly to the accompanying drawings in which like numerals indicate like parts throughout the several views, the numeral 5 generally designates the body of the

fuel pump of this invention and which is formed in two sections 6 and 7 secured together by means of screws 8 and having a flexible diaphragm 9 confined therebetween.

5 The section 6 is adapted to be secured against the side wall 10 of an internal combustion engine and has its interior hollow to accommodate diaphragm operating mechanism indicated generally by the numeral 11. The meeting faces of the body sections which confine the diaphragm therebetween are recessed in a more or less conventional manner to define a diaphragm operating chamber 12 so as to permit operating clearance for the diaphragm when the same is flexed in opposite directions in the suction and pressure strokes of the pump.

Flexing of the diaphragm is accomplished by means of a lever 13 having a bell-crank shape with the arm 14 of the lever projecting substantially horizontally out of the body section 6 for engagement of its end portion 15 with a cam 16 driven by a rotating shaft of the engine. The inner end of the arm 14 inside the pump section 6 is pivotally connected to the pump body as at 17, and the arm 18 of the lever extends upwardly from the pivot substantially at right angles to the arm 14 toward a stem 19 secured at one end to the diaphragm and extending axially therefrom into the hollow interior of the body section 6.

30 The stem 19 has a diametrically milled slot 20 through its free end and extending close to the diaphragm to receive the upper extremity 21 of the lever arm 18. A pin 22 extending through the stem on an axis transverse to the plane of the milled slot 20 is received in a substantially horizontal "bean" shaped slot 23 cut into the extremity 21 of the lever arm to provide a lost motion driving connection between the lever and the diaphragm.

40 A compression spring 24 coaxial with the stem 19 and confined between its outer free end and the wall of the body section 6 adjacent to the engine wall 10 yieldingly urges the diaphragm toward the body section 7 and has sufficient expansive force as to effect the pressure stroke of the pump. Motion of the diaphragm toward the body section 7 solely in response to the compression spring 24 in the compression stroke thus is limited by engagement of the cross pin 22 with the right hand end of the slot 23 in the lever arm 18. Hence, it will be noted that the pressure stroke of the pump is effected impositively.

45 The return or suction stroke of the pump takes place upon rotation of the cam to a position 180° opposite to that shown in Figure 1 and is effect-

ed positively through the engagement of the right hand end of the slot 23 of the lever arm with the cross pin 22 and against the action of the compression spring 24.

In this manner the diaphragm is protected against damage which might result with a positive pressure stroke when the float actuated fuel valve of a carburetor to which the pump delivers fuel closes in response to the fluid chamber of the carburetor being fully charged.

The end portion 15 of the lever arm is maintained in engagement with the cam 16 throughout its entire period of rotation by means of a separate compression spring 25 reacting between the upper end of the lever arm adjacent to the stem 19 of the diaphragm and the wall of the pump adjacent to the engine wall 10 and on a line substantially parallel with the axis of the stem and its spring 24.

The spring 25 preferably has less force than the compression spring 24 and causes the lever to follow the diaphragm in its spring propelled pressure stroke so as to limit clicking noises at its lost motion connection with the diaphragm stem.

It will be seen, therefore, that the lever 14 is oscillated on its pivot by rotation of the cam 16 and that such oscillation of the lever is translated into alternative impositive pressure and positive suction pulsations for operation of the pump.

These alternate pressure and suction pulsations are utilized to establish a flow of fuel from a supply thereof into and through the body section 7 to a carburetor or the like and for this purpose the body section 7 is provided with inlet and outlet ports 30 and 31 respectively.

In the present instance the inlet port 30 enters the side of the body section 7 remote from the diaphragm and opens to the bottom face 32 of the body section 7 through a short angular passageway 33 to direct fuel entering the pump body into a sediment bowl 34 secured to the body section 7 with its rim seated against the face 32. The conventional strap 35 passing beneath the sediment bowl and having its opposite ends engaging with a portion of the pump body serves to readily detachably connect the bowl with the body.

The conventional screen 36 and gasket 37 are preferably interposed between the rim of the sediment bowl and the seat 32 so as to form a fluid tight joint between the bowl and the pump body and to effect exclusion of undesired solid particles from the fuel delivered to the pump.

Alongside the downwardly extending branch of the passageway 33 and between it and the diaphragm chamber 12 the body section 7 of the pump is provided with a substantially vertical cylindrical cored passageway 38 opening to the face 32 of the body section 7 over the sediment bowl through an enlarged cored mouth 39 of substantially elliptical shape as clearly shown in Figure 3.

The opposite end of the passageway 38 communicates with the outlet 31 of the pump through a short cored passageway 40 having a smaller diameter than the core 38 so as to define a shoulder 41 at its juncture therewith.

A substantially elliptical plate 42 is received within the mouth 39 of the passageway and is secured to the body section 7 by means of cap screws 43 passing through holes 44 in the ends of the plate and threading into the body section 7 alongside the core 38. A gasket 45 is pref-

erably interposed between the plate and the bottom of the mouth for a purpose shortly to be described. The plate 42 also has a central aperture 46 therein coaxial with the core 38 to provide communication between it and the sediment bowl.

A pair of check valves 47 and 48 are confined within the core 38 and are retained in positions at the opposite ends of the core by means of a compression spring 49 reacting between the valves 10 to yieldingly urge the inlet valve 47 firmly against the gasket 45 and the outlet valve 48 against a gasket 50 interposed between the outlet valve and the shoulder 41 at the inner end of the core 38.

The valves are thus readily detachably sealed 15 in the core 38 against the possibility of leakage of fluid therewith and it will, consequently, be noted that the core 38 thus provides a valve chamber forming an integral part of the fluid passageway comprising the cores 38, 39, and 40 and leading to the outlet 31 of the pump.

The inlet and outlet valves operate in a conventional manner. The inlet valve 47 has a disc 51 responsive to reduced pressure within the valve chamber for establishing communication between 25 the interior of the sediment bowl and valve chamber, while the outlet valve 48 likewise has a disc 51 but its disc responds only to increased pressure in the valve chamber so that fluid therein is forced to the outlet 31 of the pump on the 30 pressure stroke of the diaphragm.

The alternate pressure and suction pulsations are manifested in the valve chamber by means of a short transverse passageway 53 leading from the diaphragm chamber to the core 38 medially 35 of its ends.

The particular arrangement of passageways and particularly that of the valve chamber enables the valves of the pump to be readily assembled in their proper positions merely by their 40 insertion into the core 38 with the plate 32 and sediment bowl 34 removed from the body section 7 and with the compression spring 49 confined between the valves. The plate 42 is then secured in the mouth 39 of the valve chamber to retain 45 both valves in their proper positions for replacement or inspection whenever desired. The pump assembly is completed upon securing the sediment bowl in place on its seat 32 of the body section 7.

50 The valves 47 and 48 are identical and each comprises a substantially cylindrical body portion 55 of a size to slidably fit the core 38, and the body 55 has a valve seat 56 provided by the junction of a bore 57 extending centrally into one end of the 55 valve body with a counterbore 58 opening to the opposite end of the body.

The valve seat 56 thus lies in a plane normal to the common axis of the bores 57 and 58, communication between which is controlled by the 60 valve disc 51 positioned within the bottom of the counterbore 58.

The valve disc 51 is preferably provided with a polygonal shape as indicated in Figure 4 to enable the disc to float freely toward and from a position 65 engaging its seat 56 during the alternate pressure and suction impulses of the diaphragm and to enable fluid to flow freely therewith when raised off its seat.

The disc 51 is yieldingly urged against its seat 70 by means of a light compression spring 60 confined between the disc and the bottom 61 of a spring cage generally indicated by the numeral 62. The spring cage has its bottom 61 formed as a disc or washer and has a number of spring arms 75 63 bent to one side thereof substantially perpen-

dicularly to the disc and inserted into the counterbore 58 for engagement of radially outwardly bent tangs 64 on the free extremities of the arms within a circumferential recess 65 cut into the side wall of the counterbore 58 near the mouth thereof.

The spring tension of the arms 63 is such that their free ends must be flexed radially inwardly for entrance to the counterbore and so that the same are capable of expanding to engage their tangs 64 within the recess 65.

It will be apparent, therefore, that each of the valves constitutes a unit capable of being made in a subassembly operation, and that a pair of such valves constitute a compact and readily assembled valve unit for the fuel pump of this invention.

From the foregoing description taken in connection with the accompanying drawings, it will be readily apparent to those skilled in the art that the fuel pump of this invention combines simplicity of design with ease of assembly and disassembly to enable its manufacture at relatively low cost.

What I claim as my invention is:

1. In a pump of the character described: a pump body; a fluid passageway in the body having an inlet and an outlet and having a valve chamber interposed therebetween; means in the pump body providing for alternately subjecting the valve chamber to reduced and increased pressure in the suction and pressure strokes of the pump respectively; a pair of check valves in said valve chamber for controlling fluid flow from the inlet to the outlet of said passageway, the movable element on one of said valves responding only to reduced pressure in the chamber on the suction stroke of the pump to permit fluid to flow into said chamber from the inlet of the passageway, and the movable element of the other of said valves responding only to increased pressure in the chamber so that fluid in the chamber is forced to said outlet on the pressure stroke of the pump; fluid seals interposed between said valves and the ends of the valve chamber for precluding fluid flow past said valves except upon response of the movable elements of the valves to pressure; and means in said valve chamber for holding the check valves in predetermined spaced apart positions within the valve chamber and against the seals at the opposite ends of the chamber.

2. In a pump of a character described: a pump body; a fluid passageway in the body including a valve chamber opening at one end to one side of the pump body to provide an inlet to said passageway, said valve chamber opening at its opposite end into said passageway adjacent to the outlet of said passageway; means in the pump body providing for alternately subjecting the valve chamber to reduced and increased pressure on the suction and pressure strokes of the pump respectively; a pair of check valve units slidably received in said chamber and located adjacent to the ends thereof for controlling fluid flow through said passageway, one of said valve units opening only in response to reduced pressure in the chamber on the suction stroke of the pump to permit fluid to flow into the inlet end of the chamber and the other of said valve units opening only in response to increased pressure in the chamber on the pressure stroke of the pump so that fluid in the chamber is forced to the outlet end of the passageway; shoulders at the opposite ends of the chamber against which the valve

units engage, one of said shoulders being located at said side of the body and being detachably secured to the body so as to enable assembly in and disassembly of the valve units from said chamber; and means interposed between the valve units to hold the same apart at the ends of the valve chamber and against said shoulders.

3. In a pump of the character described: a pump body having a fluid passageway therein, one section of said fluid passageway being enlarged and constituting a valve chamber, said body having a diaphragm chamber communicated with said valve chamber at a point substantially medially of the ends of the valve chamber; a diaphragm in said diaphragm chamber by which the valve chamber is alternately subjected to reduced and increased pressure on the suction and pressure strokes of the diaphragm respectively; a pair of check valve units slidably received in said valve chamber for controlling fluid flow through said passageway, one of said valve units being adjacent to the inlet end of the valve chamber and opening only in response to reduced pressure within the valve chamber on the suction stroke of the diaphragm to permit fluid to flow into the valve chamber from the inlet of the passageway, and the other of said valve units being located at the opposite end of the valve chamber adjacent to the outlet of the passageway and opening only in response to increased pressure within the valve chamber so that fluid in the valve chamber is forced therefrom to the outlet of the passageway on the pressure stroke of the pump; spring means interposed between said valve units for yieldingly holding the same at opposite ends of the valve chamber; and seals between the valve units and the ends of the chamber for precluding fluid flow past said valves except upon response of the movable elements of the valves to pressure.

4. In a pump of the character described: a pump body; a sediment bowl detachably mounted on the pump body with its mouth seated against one face of the body, said body having a fluid passageway the outlet of which opens to the exterior of the body remote from said face thereof, said passageway having an enlarged mouth opening to said face of the body at a point encircled by the sediment bowl and providing a valve chamber inwardly of said mouth thereof; a shoulder at the inner end of the valve chamber; means for alternately subjecting the valve chamber to reduced and increased pressure including a diaphragm; a pair of check valve units slidably received in said valve chamber for controlling fluid flow through the passageway, one of said valve units being adjacent to the mouth of the passageway and opening only in response to reduced pressure in the chamber on the suction stroke of the diaphragm so as to permit fluid in said bowl to flow into the interior of the valve chamber and the other of said valve units being disposed adjacent to the shoulder at the opposite end of the valve chamber and opening only in response to increased pressure within the valve chamber so that fluid within the valve chamber is forced to the outlet of the passageway on the pressure stroke of the diaphragm; a plate detachably secured to the pump body in the mouth of said passageway and providing a shoulder at the inlet side of the valve chamber for readily detachably retaining the valve units assembled within the pump body, said plate having an aperture therein in line with the valve chamber to permit fluid to flow from the sediment bowl to the valve chamber.

ber on the suction stroke of the diaphragm; and means within the valve chamber interposed between said valve units for holding the same spaced apart and against said shoulders.

5. In a pump of the character described: a pump body having a fluid passageway therein; means detachably connected with the pump body and forming part of the major pump instrumentalities, said means overlying one side of the pump body; inlet and outlet check valve units in said passageway, each valve unit being insertable and removable from the pump body through a counterbore opening to said side of the body which is covered by said detachable means forming part of the major pump instrumentalities; and retainer means detachably connected with the pump body and located wholly within the

10

15

body and at least partly in the counterbore through which each valve unit is removable from the body for holding said valve units in the body.

WERNER E. ARMSTRONG.
